UNITED STATES PATENT OFFICE.

CHARLES PRENTIS ELLIS AND MAURICE PATRICK O'DONOHOE, OF NASHVILLE,
TENNESSEE; SAID O'DONOHOE ASSIGNOR TO SAID ELLIS.

GAS-STOVE ATTACHMENT.

1,044,364.

Specification of Letters Patent. Patented Nov. 12, 1912.

Application filed June 21, 1911. Serial No. 634,473.

To all whom it may concern:

Be it known that we; CHARLES P. ELLIS and MAURICE P. O'DONOHOE, citizens of the United States, and residents of Nashville, in 5 the county of Davidson and State of Tennessee, have invented a new and Improved Gas-Stove Attachment, of which the following is a full, clear, and exact description.

Our invention relates generally to attachments for gas stoves and more particularly it involves a device adapted to coöperate with the gas cocks in order to prevent accidental turning of the same, thereby preventing the escape of gas save when so desired.

15 The object of our invention is to provide a new and useful attachment for gas ranges or stoves in order to prevent the handles of the cocks thereon being turned, the said means being movable to an inoperative position in order to permit the handles to be operated when it is desired to supply gas to the range or stove.

20 The invention contemplates a pivoted member mounted adjacent the handles of the gas cocks, the said member being provided with means whereby it may be moved into inoperative position, co-acting means being provided to permit it to return to operative position and be secured in such position.

25 Reference is to be had to the accompanying drawings, forming a part of this specification, in which like characters of reference denote corresponding parts in all the views, and in which—

30 Figure 1 is a plan view of our device in inoperative relation with the gas cocks; Fig. 35 2 is a perspective view of the means for controlling the movement of the same; Fig. 3 is an end view, partly in section, showing the 40 relation of the parts set forth in Fig. 2; Fig. 4 is a sectional view, on the line 4—4 of Fig. 2.

The gas cocks 1, 2, carried by any suitable gas pipe 3 adjacent a suitable stove 45 or range, are provided with the usual handles 4, 5, the air mixing chambers 6, 7, being present, the structure typifying any suitable stove or range. A longitudinally extending member 8 is pivotally supported at its ends 50 9 in suitable straps or other equivalent devices 10, 11, carried by the pipe, the member 8 being movable into two positions; in one position, as in Fig. 1, where it extends in a horizontal plane and out of the path of the

handles 4, 5, thereby permitting the same to 55 be turned, the other position being in a vertical plane or substantially at 90° of the position shown in Fig. 1, and closely adjacent the handles thereby preventing them from being turned, as particularly shown in Fig. 60 4. This member 8 is secured in position in either plane in the following way; any suitable box 12 or equivalent compartment is positioned closely adjacent one end of the member 8, the pintle on which this member 65 is mounted extending into the box and being rigidly connected to a short arm 13, this arm being in turn pivoted at 14 to a push rod 15 extending without the box through a suitable opening, the rod having a button or 70 handle 16 at its outer end. The rod 15 is provided with a plurality of projections or teeth 17, 18, either of which is adapted to engage the side wall of the opening in the box 12 through which the rod extends in 75 order to hold the rod and the member 8 in either position, as above set forth. As shown particularly in Fig. 3, the push rod has been moved into the box 12 as far as it will go, thereby bringing the tooth or projection 17 8 into engagement with the wall of the opening as before stated; the rod tends to return to position with the member 8 closely adjacent the handles of the valves by means of a helical spring 19, carried by the end of 9 the pintle on which the member is mounted, one end of this spring being in engagement with the short arm 13. The teeth or projections 17, 18, in the push rod 15 are retained in engagement with the side wall of the 95 opening in the box 12 by means of a suitable leaf spring 20 preferably on the interior of the box 12 as shown particularly in Fig. 3.

The rod is returned to normal position and the member 8 brought into operative position with respect to the handles 4, 5, in the following way; a suitable lever 21 is pivotally mounted at 22 within the box 12, this lever being in effect a bell crank, one end 23 of which bears against the rod 15, the other end of which is pivotally engaged at 24 with another push rod 25, extending without the box and having a button 26 at its end. From Fig. 3 it is obvious that after the handles 4, 5, have been brought into position to cut off the supply of gas to the range that the member 8 may be moved 90° in order to prevent further turning of the

handles by merely pressing the button 26, thereby operating the bell crank 21 and bringing the projection 17 on the rod 15 out of engagement with the side wall of the opening in the box 12 against the pressure of the spring 20, thereby permitting the helical spring 18 to move the link and the longitudinally extending member 8 into operative position when the projection 18 will be brought into engagement with the side wall of this opening, as shown in Fig. 2.

With the parts in the position shown in Fig. 3, the handles 4, 5, are free to be turned since the member 8 is retained in inoperative position because of the locked position of the rod 15; when this member 8 has been moved 90° the handles are held against turning by reason of the locked position of the rod 15, by the engagement of the tooth 18 with the opening in the box 12. When it is desired to move the member 8 into inoperative position, thereby making the handles 4, 5, available for turning, the button 16 is pushed inwardly, thereby moving the member 8 until the tooth 17 engages the side wall of the opening when the member will be held in inoperative position; after the handles have been turned to cut off the gas, the button 26 is pushed, thereby allowing the rod 15 and the member 8 to return to operative position, which is maintained as before stated by the engagement of the tooth 18 with the side wall of the opening.

From the above description taken in connection with the accompanying drawings it will be noted that we have provided an extremely simple and efficient device for preventing the turning of the handles of the gas cocks at inopportune times; the device may be used with any number of gas cocks and may be applied to any form of range or stove and may be variously changed in the size, shape and relation of its parts in order to meet varying conditions without departing from the spirit and scope of the invention as defined in the following claims.

Having thus described our invention, we claim as new, and desire to secure by Letters Patent:—

1. In combination with the gas cocks of a stove or range, a member pivotally supported adjacent the handles of the said cocks and adapted to engage them in order to prevent turning, a compartment adjacent one end of the member, a rod within the compartment and in movable engagement with the said member, the rod being provided with a number of projections adapted to engage the side wall of the compartment when the rod is moved to either of two positions, together with resilient means, one end of which engages the said member and the other end of which is fixed, whereby when one projection on the rod is released from

engagement with the side wall of the compartment, the said member will return to engagement with the said handles.

2. In combination with the gas cocks of a stove or range, a member movably supported adjacent the handles of the said cocks and adapted to be moved into engagement therewith or remote therefrom, a compartment containing resilient means in engagement with the said movable member and the said compartment, whereby the said member tends to remain in position in contact with the handles, and other means for moving the said member away from the handles, the said means having parts thereon co-operating with the said compartment in order to hold the said member in such position.

3. In combination with the gas cocks of a stove or range, a member pivotally supported adjacent the handles thereof and adapted to be moved into engagement with the handles or remote therefrom, a compartment adjacent one end of the member, resilient means within the compartment engaging the said member whereby it is retained in position in contact with the handles, a rod within the compartment and extending outwardly thereof, movement of the rod moving the said movable member, the rod having a projection thereon co-operating with the side wall of the compartment whereby the movable member and the rod are retained in such moved position.

4. In combination with the gas cocks of a stove or range, a member movably supported adjacent the said cocks and adapted to contact therewith or be moved remote therefrom, a compartment into which one end of the movable member extends, resilient means within the compartment engaging the said end of the movable member whereby it is retained in engagement with the handles, means engaging the said end whereby the movable member may be moved away from the handles and retained in such position, and other means adapted for engagement with the said means in order to release it, whereby the movable member may come back into position in contact with the handles.

5. In combination with the gas cocks of a stove or range, a member movably supported adjacent the handles of the cocks and adapted to engage them whereby they are held against turning, the said member being also adapted to be moved remote from the handles in order to allow them to be turned, a compartment adjacent one end of the said member, the end of the member entering the compartment, resilient means within the compartment and engaging the said end, a rod in engagement with the end and extending without the compartment, movement of the rod moving the said movable member, the rod being provided with a tooth adapted for

engagement with the side wall of the compartment when the said movable member is adjacent the handles in order to hold it in such position, and a second tooth on the 5 rod adapted for engagement with the side wall of the said compartment when the said movable member is remote from the handles in order to secure it in such position.

6. In combination with the gas cocks of 10 a stove or range, a member pivotally supported adjacent the handles of the cocks, a compartment into which one end of the member extends, resilient means within the compartment engaging the end of the said member, means engaging the said end for moving the member away from the handles, the said means being provided with a projection for engagement with the side wall of the compartment in order to hold the member in 15 such position, other means for releasing the projection in order to permit the movable member to return to position in engagement with the handles, and a second projection carried by the first means adapted for engagement with the side wall of the compartment in order to hold the said movable member in position in engagement with the 20 handles.

7. In combination with the gas cocks of a 25 stove or range, a movable member supported adjacent the handles of the said cocks, a compartment into which one end of the member extends, resilient means in engagement with the said end for holding the member in 30 engagement with the handles, a rod engaging the said end and extending without the compartment, there being a suitable opening in the side wall thereof, the rod being provided with a projection adapted 35 to engage the said side wall when the movable member is brought away from the handles in order to hold it in such position, there being a second projection on the rod for engagement with the side wall when the 40 member is brought into engagement with the handles in order to hold it in such position.

8. In combination with the gas cocks of 45 a stove or range, a member pivotally supported adjacent the handles thereof, an arm secured to the end of the member, a rod in engagement with the end of the arm, movement of the rod moving the said member, a fixed element adjacent the rod, the rod being provided with a projection adapted 50 for engagement with the said element when the said member is moved away from the handles in order to hold it in such position, and another projection on the rod for engagement with the said element to hold the mem- 55

ber in position when in contact with the handles.

9. In combination with the gas cocks of a stove or range, a member pivotally supported adjacent the handles thereof, an arm on the end of the said member, a rod in 60 engagement with the arm for moving it, a fixed element adjacent the rod and a tooth in the rod adapted to engage the fixed element to hold the said member away from the handles when moved to such position. 70

10. In combination with the gas cocks of a stove or range, a member pivotally supported adjacent the handle thereof, an arm on the end of the said member, a rod in 75 engagement with the arm, a fixed element adjacent the rod, the rod being provided with a number of teeth, each of the teeth being adapted for engagement with the said element, whereby the said member may be retained in position in contact with the 80 handles or removed therefrom.

11. In combination with the gas cocks of a stove or range, a member pivotally supported adjacent the handles thereof, a rod engaging the said member for moving it, a 85 fixed element adjacent the rod, the rod being provided with a tooth adapted for engagement with the element to hold the said member remote from the handles, and other means for engagement with the rod to free 75 the tooth thereon of engagement with the said element whereby the said member may return to normal position adjacent the handles.

12. In combination with the gas cocks of a 95 stove or range, a member pivotally supported adjacent the handles thereof, means for moving the member remote from the handles in order to permit turning of them, a movable member having projections thereon, a fixed element with which one of the projections, engages for holding the first means in said position, a spring, and means adapted for engagement with the first means in order to permit the spring to return the 100 said member into engagement with the said handles in order to prevent turning thereof, with the other of the said projections engaging the said fixed element.

In testimony whereof we have signed our 1 names to this specification in the presence of two subscribing witnesses.
